UNITED STATES PATENT OFFICE.

DANIEL NEIHART, OF MARTINS FERRY, OHIO.

SHEET-FEEDING DEVICE.

Application filed September 15, 1923. Serial No. 662,852.

To all whom it may concern:

Be it known that I, DANIEL NEIHART, a citizen of the United States of America, and resident of Martins Ferry, county of Belmont, and State of Ohio, have invented certain new and useful Improvements in Sheet-Feeding Devices, of which the following is a specification.

This invention relates to apparatus for feeding metal plates or sheets to a tinning pot, and it has for its primary object to provide a tank for containing a pickling fluid, water, or the like, in which the sheets are submerged prior to tinning, and mechanism associated with said tank whereby sheets of a pack submerged in the fluid of the tank are elevated therefrom one at a time and advanced to the receiving rolls of a tinning pot.

In describing the invention in detail, reference is herein had to the accompanying drawings, in which—

Figure 1 is a transverse section of the invention;

Figure 2 is an end elevation of the same;

Figure 3 is a top plan view;

Figure 4 is an enlarged sectional view of a sheet-advancing roller;

Figure 5 is a similar view of the shaft oscillating mechanism;

Figures 6 and 7 are enlarged face views of the parts which form the guides for the shiftable bar;

Figures 8 and 9 are enlarged detail views in side and front elevation, respectively, of the pack-engaging fingers; and—

Figures 10 and 11 are similar views of the adjustable pack guides.

Referring to said drawings, 1 indicates a tank of rectangular box-like form adapted to contain a bath of water or suitable pickling fluid. Journaled in the opposite ends of the tank adjacent to the front wall are parallel shafts 2 and 3, said shaft 3 being disposed above said shaft 2 and slightly forward of the vertical plane in which the latter is located. The shaft 3 has fixed thereon a plurality of rollers 4, each having on its peripheral surface a covering 5 of a soft or resilient material, preferably soft rubber; and the shaft 2 likewise has thereon a plurality of rollers 6 which either may be keyed for rotation with the shaft or may be loose so that they and the shaft rotate independently.

The rollers 4 and 6 are adapted for having rest thereagainst the foremost sheet 7 of a

pack 8 of sheets which is disposed within the tank in a slightly inclined position with the lower edge thereof seated upon a plurality of bars 9 forming parts of a pack support. 60

Located rearward of and in engagement with the rearmost sheet of the pack are the fingers 10 of a device whereby pressure is constantly exerted for maintaining the pack in the forwardly thrust position in which the foremost sheet rests closely against the two sets of rollers 4 and 6. As herein shown for purposes of illustration, said pressure device comprises a horizontal bar 11 which has its opposite ends disposed for sliding movement 65 in channel-like guideways 12 provided in bars 13 fixed upon the inner faces of the opposite end walls of the tank. Said fingers 10, which are fixed upon said bar 11, are each bent to form a curved bar-over-hanging portion 10^a and a downwardly and rearwardly inclined main body portion, said portion 10^a being designed as supports over which the pack 8 is passed in introducing the latter in the tank, and the main body portion is downwardly and rearwardly inclined to correspond substantially with the inclination of the pack when the latter occupies its inclined position in seated relation to the two sets of rollers 4 and 6. 75

Adjustably mounted upon the opposite end portions of the bar 11 are guide members 14 which, as herein shown, are disposed vertically, but they may be of any suitable form adapted to facilitate the work of entering the packs in a position substantially midway between the ends of the tank. A laterally extending lip 16 formed on or carried by each guide member 14 rests upon the bar 11 and has an adjusting pin or bolt 17 directed vertically therethrough and slidable in a slot 18 provided therefor in said bar. 85

Attached to the bar 11 adjacent to each of its ends is an end of a cable or chain 19 which extends horizontally forward to and over a pulley 20 carried by a bracket 21 mounted on a wall of the tank, and the opposite end of said cable or chain has suspended thereon a suitable weight 22. Said weights act through said chains normally to maintain the bar 11 advanced in the position in which the fingers 10 bear upon the pack for holding the latter in its most advanced position and to still further advance the pack as each sheet thereof is withdrawn. 100

The pack support comprises, in addition to the bars 9, a pair of transverse supporting

bars 23 which are suitably suspended in horizontal positions, as by chains 24, from bracket posts 25 mounted upon the ends of the tank, said chains being adjustable for suspending said bars at the desired elevation to suit packs of sheets of different dimensions. The body portions of the bars 9 upon which the packs are carried are downwardly and forwardly inclined, as shown in Fig. 1, for facilitating the advance movement of such packs.

The friction between the coverings 4 of the rollers 3 and the therewith engaged foremost sheet of the pack is sufficient to effect elevation of said sheet when said rollers are rotated in a forward direction. So elevated, each successive sheet falls over upon guide members 26 whereon it may be advanced by any preferred means (not shown) to the tinning pot, which latter may occupy a position located closely adjacent to the foremost wall of the tank 1. For preventing the advance of more than one sheet at a time from the tank, one or more dogs 27 are pivoted in suitable positions, as upon a bar 28 mounted upon the top of the tank, each of said dogs having its free, or pointed, end so positioned that, whilst it permits the foremost sheet of the pack to rise thereby unobstructedly, it will promptly engage the upper edge of the next sheet rearward of said foremost sheet, should such next sheet start to rise with said foremost sheet, and will positively prevent further advance thereof until after said foremost sheet has passed to a point at which the entire pack, actuated by the pressure of the fingers 10, is advanced against the rollers 4 and 6. Springs 29 supported by brackets 30 maintain said dogs 27 depressed under yielding tension.

The upper shaft 3 is positively driven, as by power applied thereto through a belt wheel or pulley 31 fixed on a projecting end thereof; and power for driving the lower shaft 2 is communicated to the latter from said shaft 3, as by a sprocket chain 32 connecting sprocket wheels 33 and 34 carried by said shafts 3 and 2, respectively.

Either one or both of the shafts 2 and 3 may be arranged for slight rapidly-shifting longitudinal movement during rotation thereof, such arrangement having for its purpose to induce rapid oscillatory movements of the foremost sheet for effecting such loosening of the latter from the next adjacent sheet that it may be advanced with a minimum of resistance from the latter. The mechanism by which such oscillations of each shaft is induced comprises an outwardly facing plate 35 carried by an end wall of the tank 1, said plate as herein shown being formed integral with a stuffing box 36 in said wall. A gland 37 embracing the shaft cooperates with said stuffing box in

the usual manner. The outer face of said plate 35 has formed thereon spaced radial teeth 38 upon which ride similar teeth 39 formed on the adjacent face of a collar 40 which is fixed on the shaft. A spiral spring 41 which encircles the shaft has its inner end resting against said collar and its outer end seated against the shaft embracing end portion 42^a of a bracket 42 carried by the adjacent end of the tank.

In practice, forward rotation of the shaft carries the teeth of the collar 40 over the teeth of the plate 35, thus effecting alternate outward shifting of the shaft against the tension of the spring 41 and inward shifting of the shaft actuated by the released force stored by compression of said spring.

The coverings 5 for the rollers 4 may be either plain, as shown in Fig. 4, or they may have therein holes or sockets 43 adapted to form so-called vacuum cups for increasing the pull exerted by said coverings on the engaged sheets.

What is claimed is—

1. A metal-sheet feeding device comprising a fluid-containing tank, shafts journaled within said tank, a plurality of rollers carried by each of said shafts, a support upon which a pack of sheets seats in edgewise position, automatic pack advancing means whereby said pack is held in a forwardly thrust position on said support in which it rests closely against said rollers, said means including fingers having curved upper portions over which the pack is guided to position in introducing the latter means for rotating the uppermost of said shafts for frictionally elevating the foremost sheet of the pack, and means permitting elevation of but one sheet at a time.

2. A metal-sheet feeding device comprising a fluid-containing tank, shafts journaled within said tank, a plurality of rollers carried by each of said shafts, said rollers being submerged in the fluid of said tank, a support upon which a pack of sheets seats in edgewise position, guides carried by said tank adjacent to the opposite lateral edges of the pack, a transverse bar slidable in said guides, means carried by said bar for seating against the rear face of the pack, means connected to said bar whereby the latter is actuated to maintain the pack in a forwardly thrust position in which it rests closely against said rollers, means for rotating one of said shafts for effecting elevation of the foremost sheet of the pack by the friction of the rollers carried by said shaft, and pivoted dogs guarding against elevation of other than such foremost sheet.

3. A metal-sheet feeding device comprising a fluid-containing tank, shafts journaled within said tank, a plurality of rollers carried by each of said shafts, said rollers being submerged in the fluid of said tank, a

support upon which a pack of sheets seats in edgewise position, adjustable suspension means for said support, guides carried by said tank adjacent to the opposite lateral edges of the pack, a transverse bar slidable in said guides, means carried by said bar for seating against the rear face of the pack, means connected to said bar whereby the latter is actuated to maintain the pack in a for-

wardly thrust position in which it rests 10 closely against said rollers, and means for rotating one of said shafts for effecting elevation of the foremost sheet of the pack by the friction of the rollers carried by said shaft. 15

In testimony whereof, I affix my signature.

DANIEL NEIHART.
